UNITED STATES PATENT OFFICE.

HARRY N. KNOWLTON, OF CHICAGO, ILLINOIS, ASSIGNOR TO WEYERHAEUSER FOREST PRODUCTS, OF ST. PAUL, MINNESOTA.

CRATE.

Application filed November 8, 1923. Serial No. 673,420.

The present invention relates to crates and its general object is to economize in the use of lumber and at the same time to increase the rigidity and strength of the crate. 5 A further object of the invention is to provide a crate so constructed for the specific purpose of packaging automobiles for export shipment in such manner as to reduce the displacement of the package to a minimum.

In the drawings, which illustrate a preferred form of crate embodying the invention,—

- 15 Figure 1 is a plan view of the bottom.
- Figure 2 is an end view of the bottom.
- Figure 3 is a side view of the bottom.
- Figure 4 is an inner view of one of the sides.
- Figure 5 is an end view of the side.
- 20 Figure 6 is a view looking at the bottom edge of the side.
- Figure 7 is an inside view of one of the ends.
- Figure 8 is an end view of the end.
- 25 Figure 9 is a view looking at the lower edge of the end.
- Figure 10 is a longitudinal section of the assembled crate.
- Figure 11 is a section on the line 11—11 30 in Figure 10.

The bottom, the ends, the sides, and the top of the crate are constructed as separate units which may be secured together to complete the crate. The bottom is formed by longitudinally extending beams or sills 1 to serve as skids and are laterally spaced apart and secured together by a plurality of longitudinally spaced transverse bars 2. The skids are further secured together at 35 each end by transverse bars 3 and 4, the outer bars 4 being somewhat shorter than the bars 3 so as to expose surfaces 5 of the skids at the several corners of the crate. A plurality of longitudinally extending boards 6 are fitted together and secured to the under surfaces of the bars 2, 3 and 4, the under surface of the flooring formed by the boards 6 being above the level of the under surfaces of the skids 1. Longitudinal rails or runners 7 are secured to the respective skids 1,

preferably in abutting relation to the ends of bars 2 and are inset from the outer edges of the skids. As shown in Figures 1, 3 and 10, I prefer to reinforce the transverse tie bars 2 with cleats 2^a nailed or otherwise secured to the rails 7. 55

Each of the ends of the crate is made up of vertically disposed boards 8 fitted together, the boards being secured together by a transverse member 9 at the top of the end, 60 a transverse member 10 near the bottom of the end but above its lower edge, and a diagonal brace 11. At its opposite ends the end unit is provided with a vertical post 12 which extends downwardly to the bottom edge of the unit and upwardly to the lower edge of the transverse member 9, the latter being shorter than the complete unit so as to expose the top surfaces 13 of the end posts and to provide a recess 13^a. 65

Each of the side units of the crate is made up of vertically disposed boards 14 secured together by a longitudinal member 15 somewhat above the lower edge of the unit, by a longitudinal member 16 at the top of the 70 unit, and by suitable braces 17.

The top of the crate is formed by longitudinally extending boards 23 fitted together and secured together by transverse members 22. When the top is in position in the assembled crate it is also supported by cross bars 21 resting on cleats 18 secured against the inner faces and below the top edges of the longitudinal members 16 at the upper edges of the side units. The bars 21 and the bars 22 preferably alternate with each other. 75

For the purpose of carrying out the specific object of packaging automobiles for export shipment blocks 19 are secured to the skids 1 toward one end of the crate and the blocks are provided with suitable fastening devices, such as bolts and straps 20, for securing the ends of an automobile axle on the blocks. 80

In the construction of the crate the bottom, side, end and top units are separately constructed as described, and then assembled to complete the crate. In the assembled crate the bottom ends of the posts 12, with which 85

each of the end units is provided, rest on the exposed surfaces 5 of the skids 1 at the several corners of the crate, the sides of the lower ends of the posts bearing against the ends of the transverse bars 4 and the ends of longitudinal rails 7. The lower transverse member 10 of the end unit rests on the upper face of the transverse bar 4 and aids in accepting loads that may be placed upon the 10 top of the crate to transmit such loads to the bar 4 and thus to the skids 1 where they are absorbed. Reinforcing corner braces or cleats 10^a may be used if desired. In the assembled crate the lower longitudinal members 15 of the side units rest on the outer portions of the upper sides of the skids 1 and bear against the outer faces of the longitudinal rails 7. The ends of the upper longitudinal members 16 of the side units rest 15 on the upper ends 13 of the posts 12 where they enter recesses 13^a, while the ends 14^a of the side units may preferably overlap the ends 12^a of the end units falling flush with the outer side thereof as will be understood. 20 The top unit, formed by the boards 23 and cross bars 22, rests on the upper edges of the side units and the end units and is further supported by the cross bars 21 which rest on the cleats 18 secured to the side units thus 25 placing any load falling upon the top unit upon the vertical side and end units. The several units are securely nailed and spiked together and in addition to the parts described various cleats may be used as desired. 30

It will be noted that the completed crate is provided on its under side with skids which form the supporting base of the crate and which prevent injury to the floor of the 40 crate if the crate be dragged along a pier or the floor of a building. The skids are securely and rigidly tied together and the end units and side units are directly supported by the skids themselves. Furthermore the 45 side units are also supported by the posts of the end units, thus effecting not only the additional support and strengthening of the sides but also the bracing of the ends and the tying of all of the units together on the 50 skids. It is advantageous to have the boards of the side units vertically disposed because they can all be secured together and supported by the longitudinal members 15 which rest on the skids and by the longitudinal members 55 16 which rest on the posts of the end units and because great stresses will be successfully resisted by the wood in the direction of its grain length. Similarly it is advantageous to have the boards of the end units vertically disposed because they can all be secured to and supported by the lower transverse member 10 which rests on the transverse bar 4 supported on the skids. It is also of advantage to have the boards of the floor and 60 65 top of the crate extend longitudinally be-

cause they can be secured to the several transverse bars, thus increasing the strength and rigidity of the crate.

The crate illustrated is specially designed for packaging automobiles for export shipment. For such shipment the wheels and top of the automobile are removed, the wheels usually being hung on the sides of the crate and the top usually being secured over the engine hood. The entire weight of the rear end of the car is supported on the blocks 19 on which the ends of the rear axle rest and to which the axle is secured by the fastening devices 20. The running boards and fenders extend outwardly over the rails 7 and the longitudinal members 15 and only slightly clear the inner faces of the side boards 14 while the braces 17 are arranged to clear the slopes of the fenders. The top of the back seat just clears the top of the 85 crate and the ends of the car just clear the ends of the crate. The construction of the crate as described makes it possible thus to package the car with very little clearance without sacrificing, but rather increasing, the 90 strength and rigidity of the crate as compared with crates usually used for the purpose. Of course, the freight on export shipments of this character is computed by displacement and the present invention has effected a very large saving in freight payments by exporters of automobiles and at the same time has increased the strength and safety of the package. 95

Having described my invention, what I claim is:—

1. A crate comprising, laterally spaced longitudinal skids, a floor composed of longitudinally extending pieces secured to and between the skids and having its top surface flush with the top surfaces of the skids, longitudinally spaced transverse bars secured to the tops of the skids, end walls supported by the skids, side walls supported by the skids and end walls, a top supported on the end walls and side walls, blocks respectively secured to the skids toward one end of the crate and means for securing the ends of an automobile axle on the blocks. 105

2. A crate, comprising laterally spaced longitudinal skids, transverse end bars secured to the skids, longitudinally spaced transverse intermediate bars secured to the skids, longitudinal rails respectively secured to the skids, a floor composed of longitudinally extending pieces secured to the bars and having its bottom surface above the bottoms of the skids, end walls composed of vertically extending pieces and having vertical posts at their ends and a member extending between the posts near the lower edge of the wall, the posts resting on the skids and the members respectively resting on the end bars, side walls composed of vertically extending pieces and having longitudinal members 110 115 120 125 130

near their bottom and top edges, the bottom members respectively resting on the skids and against the rails and the top members resting on the posts, and a top supported on the end walls and side walls.

3. A crate, comprising laterally spaced longitudinal skids, transverse end bars secured to the skids, longitudinally spaced transverse intermediate bars secured to the skids, longitudinal rails respectively secured to the skids, a floor composed of longitudinally extending pieces secured to the bars and having its bottom surface above the bottoms of the skids, end walls composed of vertically extending pieces and having vertical posts at their side edges, and a member extending between the posts near the lower edge of the wall, the posts resting on the skids and the members respectively resting on the end bars, side walls composed of vertically extending pieces and having longitudinal members near their bottom and top edges, the bottom members respectively resting on the skids and against the rails and the top members resting on the posts, a top supported on the end walls and side walls, blocks respectively resting on the skids and against the rails toward one end of the crate, and means for securing the ends of an automobile axle on the blocks.

4. In a crate construction, a plurality of members adapted to serve as skids, sheathing arranged between said skids, above the bottoms and substantially flush with the tops thereof to form a flooring, runner members secured to said skids intermediate the side edges and extending lengthwise of the top faces thereof, tie members forming securing means for said sheathing and extending between said runner members and cooperatively connected thereto to horizontally brace the structure formed, and means constructed and arranged to support a crated article above said skids whereby stresses imposed by said article are transmitted to said skids.

5. In a crate construction, a plurality of members adapted to serve as skids and primary supporting means, runner members secured to the top faces of said skids intermediate of the side edges and extending lengthwise thereof, tie members extending between said runner members and cooperatively connected thereto to horizontally brace and space the structure thus formed, side units having supporting means engaging the top faces of said skids adjacent said runner members, and end units having means to engage a top portion of said side units for the support and security thereof, said end units being supported through the medium of the top faces of the ends of said skids.

6. A structural corner construction for a

crate comprising, a primary supporting sill, 65 a runner on top of said sill, extending longitudinally and spaced from the edge thereof to provide a ledge, a wall structure positioned and supported by said ledge and adjacent edge face of said sill and means to 70 support the weight of an article to be crated directly upon said sill.

7. A structural corner construction for a crate comprising, a sill forming a primary support, a runner atop said sill and intermediate the side edges thereof to provide a ledge, a wall structure positioned and supported by said ledge, the adjacent edge face of said sill and the adjacent side face of 75 said runner, and means to support the weight of an article to be crated arranged upon the opposite ledge in abutting relation to the correspondingly adjacent face of said runner.

8. A structural corner construction for a crate comprising a sill forming a primary support, a runner extending longitudinally of the top face of said sill, intermediate the side edges and terminating short of the ends thereof to provide ledges at the sides and ends of the top face of said sill, side and end wall structures supported upon said ledges with portions in abutting relation to the ends and one side face of said runner, 90 and means to support the weight of an article to be crated arranged upon the other side ledge in abutting relation to a side face of said runner.

9. An automobile crate comprising a plurality of spaced longitudinal skids, flooring connecting said skids, side and end wall units secured to said skids and a brace structure for said side wall units so constructed and arranged as to clear running boards and fenders of the enclosed automobiles, thus permitting the said side walls to substantially abut the running boards and fenders, and whereby the transverse dimensions of the crate may be reduced to a minimum.

10. A crate comprising laterally spaced longitudinal skids, a floor secured to the skids and forming therewith a bottom unit, end wall units having vertical posts at their ends resting on said skids, side wall units 115 having longitudinal members near their bottom and top edges respectively, the bottom members resting on said skids and the top members resting on said posts, and a top unit supported on said side and end 120 wall units.

11. A crate comprising a bottom unit, two pairs of wall units, one pair of said wall units having vertical posts at their ends resting on said bottom unit, the other pair of said wall units having longitudinal members near their top edges, said members being adapted to rest on and be supported by

said posts and a top unit supported on said wall units.

12. A crate comprising laterally spaced longitudinal skids, a floor secured to said skids and forming therewith a bottom unit, a pair of opposed wall units supported by said bottom unit and having vertical posts at their ends, a second pair of opposed wall

units supported by said bottom unit and having longitudinal members adjacent their top edges, said members resting on said posts and a top unit supported on said wall units.

In witness whereof, I hereunto subscribe my name this 29 day of October, 1923.

HARRY N. KNOWLTON.
